UNITED STATES PATENT OFFICE.

VICTOR J. ROBIN, OF BUTTE, MONTANA.

PLUMBER'S TORCH.

1,322,952.

Specification of Letters Patent. Patented Nov. 25, 1919.

Application filed April 19, 1919. Serial No. 291,368.

To all whom it may concern:

Be it known that I, VICTOR J. ROBIN, a citizen of the Republic of France, residing at Butte, in the county of Silver Bow and 5 State of Montana, have invented certain new and useful Improvements in Plumbers' Torches, of which the following is a specification.

This invention relates to a plumber's or 10 blow torch, and an object of the invention is to provide a pilot heating device which derives its fuel from the fuel containing tank of the torch structure, an object of the invention being to provide a pilot burner 15 by means of which the regular burner of the torch may be quickly and easily heated to the desired temperature prior to the permitting of passage of fuel thereto without the necessity of employing any exterior 20 agent or fuel for heating the said burner.

In the ordinary or approved construction of plumbers' torches now in use, a cup is carried by the feed pipe which leads from the fuel container to the burner of the torch 25 and in using the torch structure, this cup is filled with alcohol or analogous fuel which is ignited, for heating the burner of the torch to the desired temperature. This construction, however, has numerous inconveniences, and undesirable features, among 30 which are, that extra fuel must be carried by the user of the torch to fill the cup when he desires to light the torch and furthermore the cup is generally positioned so that 35 other parts except the burner of the torch are heated, and furthermore with cups of this nature, it is generally rather difficult to heat the burner to the desired temperature.

It is an object of this invention to provide 40 a pilot burning attachment including a capillary wick, which extends into the fuel in the ordinary retaining tank of the blow or plumber's torch and which leads to a suitable valve coupling, upon which is 45 detachably connected a burner of coiled pipe of suitable material having a nut attached to the ends of the coil of which the burner is formed, which nut is adapted for connection with the valve casing to permit 50 the passage of fuel into the burner and also to provide a wick which extends partially through the burner for feeding the fuel upwardly thereabout, providing portions of the convolutions of the burner above the 55 outlet openings, so that the fuel upon its passage to said outlet openings will be

heated for converting into gas to provide the proper "blue" flame to insure the proper heating of the burner of the torch.

Other objects of the invention will appear from the following detailed description taken in connection with the accompanying drawings; forming a part of this specification and in which drawings:

Figure 1 is a side elevation of an ordinary plumber's or blow torch showing parts thereof in section, and having the improved pilot burner applied thereto.

Fig. 2 is a section on the line 2—2 of Fig. 1 and

Fig. 3 is a detail side elevation of the pilot burner having parts thereof in section to illustrate the capillary wick therein.

Referring more particularly to the drawings, 1 indicates an ordinary plumber's or blow torch of approved type which includes the receptacle or retainer 2 for the liquid fuel, and with the interior of which retainer, the pump structure 3 communicates for pumping air into the container to permit the air to become impregnated with the liquid fuel within the container for feeding to the burner 4 of the torch, to which burner the passage of fuel is controlled by the usual valve construction 5.

The pilot burner structure which is employed for initially heating the burner 4 to the necessary temperature to insure the proper combustion of the fuel fed thereto, is generically indicated by the numeral 10 and comprises a relatively short length of pipe 11 which is threaded into the feed pipe 6 of the torch structure and is connected to or has formed thereupon a valve casing 12. This valve casing 12 is provided with a relatively small tortuous pathway 13 which communicates with the interior of the pipe 11 and with the upper end of the casing, opening up through the latter into a nut 14 which is detachably connected to the valve casing 12. This nut 14 is hollow and has cotton or analogous capillary material stuck therein, as shown at 15. The capillary material is provided with an elongated relatively fine extension 16 which extends upwardly into the upwardly extending portion 17 of the burner structure proper 18 of the pilot burner 10. The burner structure 18 of the pilot burner structure 10 is preferably formed of relatively small pipes of any suitable material, and it is bent to provide a convolution providing a pair of

- 2 substantially horizontal portions 19, one of which has communication with the upper end of the upwardly extending portion 17 of the burner, while the other one has communication with the upper end of the upwardly extending portion 20 of the burner, as clearly shown in the drawings. The lowermost portion of the convolution of the burner 18 is provided with an outlet opening 20 through which the fuel egresses for burning, and this opening is positioned directly beneath the horizontal portion 19 so that the fuel which is fed upwardly from the receptacle or container 2 by means of a capillary wick 16 and 15 and the capillary wick 22 which extends into the liquid fuel in the receptacle and through the pipe 11 into the valve casing 12 will be vaporized, and converted into a volatile gas to insure the result of maximum heat therefrom upon its exit from the burner opening 20' and when ignited thereat, for heating the burner 4 of the torch structure to the desired temperature.
- 25 The flow of the volatile fuel through the tortuous passageway 13 in the valve casing 12 is controlled by a valve stem 23 threaded into an extension 24 formed upon the valve casing 12 and provided with a suitable button 25 upon its outer end to facilitate the manual rotation of the stem 23 to move its inner end into and out of the valve seat 26 which is formed in the valve casing 12 and interrupts the passageway 13.
- 30 In use, the valve 23 is unseated, and by a few operations of the pump 3, the fuel will be fed or carried upwardly by the wicks 22, 15 and 16, into the burner 18 and may be ignited at the opening 20' to properly heat the burner 18 and in turn heat the burner 4. After the burner 4 has been heated to the desired temperature the valve 21 is seated, cutting off the supply of fuel to the burner 18 and the valve 5 is opened, permitting the fuel to flow through the burner 4 of the torch structure.
- 35 Changes in details may be made without departing from the spirit of this invention, but;
- 40 I claim:
1. The combination with a plumber's torch including a burner and a fuel retainer for supplying fuel to the burner, of a pilot burner including a tube coiled to provide a convolution and a pair of lead sections leading to said convolution, said tube provided
- 45 with an upwardly directed burner opening in the lowermost portion of the convolution for directing the flame upwardly about the upper part of the convolution, capillary wicks in said lead sections of the burner, and means communicating with said pilot burner and fuel retainer to feed fuel to said capillary wick. 60
- 50 2. The combination with a plumber's torch including a burner and a fuel retainer for supplying fuel to the burner, of a pilot burner including a tube coiled to provide a convolution and a pair of lead sections leading to said convolution, said tube provided with an upwardly directed burner opening in the lowermost portion of the convolution for directing the flame upwardly about the upper portion of the convolution, capillary wicks in said lead sections of said burner, a capillary wick extending into said fuel retainer to feed fuel to said first-named wicks, and a valve for controlling the feeding of fuel to said capillary wick. 70
- 55 3. The combination with a plumber's torch including a burner and a fuel retainer for supplying fuel to the burner, of a valve casing, a nut threaded upon one portion of said valve casing, a burner carried by said nut and including a tube coiled to provide a convolution, and a pair of lead sections leading to said convolution, said tube provided with an upwardly directed burner opening in the lowermost portion of the convolution for directing the flame upwardly about the upper portion of the convolution, and a capillary wick extending into said fuel retainer and said valve casing for feeding fuel to the valve casing. 80
- 60 4. The combination with a plumber's torch including a burner and a fuel retainer for supplying fuel to the burner, of a valve casing, a nut threaded upon one portion of said valve casing, a burner carried by said nut and including a tube coiled to provide a convolution, a pair of lead sections leading to said convolution, said tube provided with an upwardly directed burner opening in the lowermost portion of the convolution for directing the flame upwardly about the upper portion of the convolution, a capillary wick extending into said fuel retainer and said valve casing for feeding fuel to the valve casing. 90
- 65 5. The combination with a plumber's torch including a burner and a fuel retainer for supplying fuel to the burner, of a valve casing, a nut threaded upon one portion of said valve casing, a burner carried by said nut and including a tube coiled to provide a convolution, a pair of lead sections leading to said convolution, said tube provided with an upwardly directed burner opening in the lowermost portion of the convolution for directing the flame upwardly about the upper portion of the convolution, and a capillary wick extending into said fuel retainer and said valve casing for feeding fuel to the valve casing. 95
- 70 6. The combination with a plumber's torch including a burner and a fuel retainer for supplying fuel to the burner, of a valve casing, a nut threaded upon one portion of said valve casing, a burner carried by said nut and including a tube coiled to provide a convolution, a pair of lead sections leading to said convolution, said tube provided with an upwardly directed burner opening in the lowermost portion of the convolution for directing the flame upwardly about the upper portion of the convolution, a capillary wick extending into said fuel retainer and said valve casing for feeding fuel to the valve casing. 100
- 75 7. The combination with a plumber's torch including a burner and a fuel retainer for supplying fuel to the burner, of a valve casing, a nut threaded upon one portion of said valve casing, a burner carried by said nut and including a tube coiled to provide a convolution, a pair of lead sections leading to said convolution, said tube provided with an upwardly directed burner opening in the lowermost portion of the convolution for directing the flame upwardly about the upper portion of the convolution, and a capillary wick extending into said fuel retainer and said valve casing for feeding fuel to the valve casing. 105
- 80 8. The combination with a plumber's torch including a burner and a fuel retainer for supplying fuel to the burner, of a valve casing, a nut threaded upon one portion of said valve casing, a burner carried by said nut and including a tube coiled to provide a convolution, a pair of lead sections leading to said convolution, said tube provided with an upwardly directed burner opening in the lowermost portion of the convolution for directing the flame upwardly about the upper portion of the convolution, a capillary wick extending into said fuel retainer and said valve casing for feeding fuel to the valve casing, and capillary wicks in the lead sections of said burner adapted to receive fuel from said first-named capillary wicks. 110
